UNITED STATES PATENT OFFICE.

CHARLES ALBERT KELLER, OF PARIS, FRANCE.

ELECTRIC FURNACE.

986,179.

Specification of Letters Patent.

Patented Mar. 7, 1911.

Application filed February 26, 1904. Serial No. 195,324.

To all whom it may concern:

Be it known that I, CHARLES ALBERT KELLER, a citizen of the Republic of France, and a resident of No. 3 Rue Vignon, Paris, in France, engineer, have invented certain new and useful Improvements in and Relating to Electric Furnaces, of which the following is a specification.

- This invention relates to an electrical furnace having a plurality of hearths connected by one or more channels adapted to receive fluid metal which is reduced at and flows from each hearth, the channel or channels being arranged preferably below the level of fusion of the materials in the different hearths, and being so placed that the electrical current can, at any given moment, be closed so as to pass through its or their contents.
- 20 In the accompanying drawings employed for purposes of explanation: Figure 1 is a longitudinal section, Fig. 2 is a horizontal section through line 2—2 of Fig. 1, and Fig. 3 a longitudinal section illustrating the means for reheating described hereinafter. Fig. 4 is a diagrammatical representation of the furnace, showing the electrical connections and indicating by arrows the directions of flow of the electric current.
- 30 In this furnace a strong electric current from a dynamo or other suitable source of electricity A enters by means of main conductor B and shunt conductors B¹ and B², the vertically movable electrodes a, a', from whence the current flows in a manner hereinafter set forth, to electrodes b, b', and thence back to the source of supply by means of the shunt conductors C¹, C², and the main conductor C.
- 40 Where four hearths are combined, as c, c, c, c, they are divided into two groups combined one with the other, the two hearths in each group being placed in parallel. This system offers a particularly practical arrangement where four hearths are arranged in the form of a cross and which will connect with a centrally disposed crucible d which is thus made very accessible. This arrangement which is considered preferable is, however, only given as an example. It will be well understood that the system described requires at least two hearths.
- 50 The crucible d previously mentioned is adapted to contain the materials according to the extent to which they have been melted in hearths c, c, c, c; they are thus kept heated

and are combined in quantities as desired, and can therefore be withdrawn in one body through an orifice, i. After a suitable quantity of material has been melted and is contained in the hearths c and crucible d, the electric circuit is maintained as follows:—From generator A through conductor B, shunt conductors B¹ and B² to electrodes a' and a respectively, from electrode a' to electrode b through molten material in the direction of the arrow shown in the upper part of crucible d in Fig. 4, and simultaneously from electrode a to electrode b' through the molten material in the direction of the arrow shown in the lower part of crucible d in said figure, through electrodes b and b' and shunt conductors C¹ C² respectively to main conductor C, and back to generator A. It will thus be understood that the electrodes a and a' are of the same polarity, and the electrodes b and b' are of opposite polarity to the electrodes a and a'.

It should be observed here that, in such a system, when the tapping takes place, the electrical circuit could be broken by the withdrawal of the metal, as these materials serve as conductors connecting the hearths through which the current enters and leaves.

For the purpose of avoiding inconvenience in certain cases, whereby not only an entire stoppage of the function of the apparatus would be produced but also interference with the machines for generating the current, there may be provided between the two groups of hearths of different polarity electrical connections and between each two groups of hearths of like polarity electrical shunt connections are provided. For such purpose the bottom of each hearth is made of electrically conductive material c' and they are connected with bars of copper, e, e, which connect the bottoms of each group of hearths, as shown in Fig. 2. That is, one copper conductor e connects the bottoms of the hearths c in which the vertically movable electrodes a and a' are disposed, and the other copper conductor e connects the bottoms of the hearths c in which the two electrodes of opposite polarity, namely electrodes b and b', are disposed. A conductor e' connects the two conductors e, e, as is shown in Figs. 1 and 3, and by dotted lines in Fig. 2. Each of the conductors e, is therefore divided into two approximately equal shunt portions, e² e³.

During the pouring operation, the inten-

sity of the current passing through the fused mass in the channels f , f , connecting the hearths, c , c , and in the crucible d diminishes until it practically becomes nothing toward 5 the end of the pouring of the metal. The current then flows through the two electrodes a and a' , and their corresponding conducting bottoms c' , c' , through the shunt conductors e^3 and e^2 respectively, to conductor e^1 (which conductor connects the two groups of hearths of opposite polarity) through said conductor, through shunts e^2 , e^3 conducting bottoms c' , c' to the electrodes b , b' , respectively, the current increasing in 10 said conductors as the resistance to the passage of the current in the fused mass becomes greater. The moment that the fused mass is insufficient to electrically connect the materials which are being treated in the two 15 groups of hearths of opposite polarity, the entire current will flow through the conductors e^2 , e^3 , e^1 , aforesaid. After the tapping the fused materials as they are reduced from hearths c , gather in canals f and crucible d , and part of the current begins to 20 flow through the fused mass inversely in proportion to the resistance in such fused mass and conductors e^2 , e^3 , e^1 . When a sufficient mass of fluid metal has accumulated, 25 the greater part of the current will pass through the said fluid mass, and only a part through conductors e^2 , e^3 , e^1 , it being understood that the use of the latter is only for the purpose of maintaining the passage 30 of the current through the furnace after a tapping and to get the fusion of a fresh charge started. It will therefore be understood that a portion of the current will always pass through the external conductors 35 e^2 , e^3 , e^1 , the current dividing inversely as the resistances of the fused mass and of the said external conductors. The putting back into the circuit of the fused mass connecting the hearths is thus automatic and progressive. Thus, there is no fear of irregularity 40 or variation in the distribution of the electrical current.

The advantages of multiple hearth furnaces so referred to are particularly as follows: In the reduction of ore the reduced metal flows as it is being fused into the central portion which as stated can be arranged in the form of a crucible and wherein the purification and refining can take place; the crucible can, for that purpose, be lined with a suitable composition. It is provided with a suitable opening for the introduction of proper additional material, and it may also be provided with a twyer t for the introduction of any suitable kind of gas. If such introduction into the body of the liquid produces an oxidizing action it will not, in consequence, consume the electrodes which are preferably elongated and out of reach

of the zone of introduction. Besides, a sample of the metal can easily be taken to determine the condition of the metal before pouring it.

The operation of the apparatus is as follows: The hearths, c , c , are filled with material through a considerable portion of which the current flows. Considering for instance the treatment of iron ore a mixture of said ore, coke and flux will fill hearths c , c , c , c . Under the action of the heat due to the passage of the electric current the fusing will take place, the fused metal in each of the channels flowing to its bottom and then uniting in the crucible d which gradually fills up; the distribution of the electrical current then takes place as before described. To the fused mass which is more or less carbureted and which has gathered in the crucible d heat can be applied for the purpose of dephosphorization, and an oxidizing zone can be provided in the crucible into which air may be blown for the purpose of refining.

When the metal in the crucible has been brought to the proper condition it is withdrawn by pouring it.

In the case of treatment of copper ore, to consider another case, the fusion of the metal will take place in each of the hearths c , c , and the mass will become separated from the dross by gravity in the central crucible d into which air may be blown for the purpose of refining.

In the two cases cited the great industrial advantages will be noted which are to be gained by the use of a multiple hearth furnace due to the accessibility of the liquid mass.

In case the temperature of the liquid contained in the central crucible should not be sufficiently high, there is provided in the crown of the crucible (Fig. 3) an opening closed by a plug g , which plug can be removed for the purpose of inserting in the opening a movable vertical electrode h , connected in parallel to one of the two poles but shown in the drawings connected to the positive conductor, the arrows representing the direction of flow of the current which has entered said electrode h ; in moving said electrode up and down, the passage of the current for reheating purposes can be easily regulated. When the electrode h is in use, it will be readily seen that a portion of the current will pass from conductor B by means of the conductor B' , through said electrode, and the current will then pass in the direction of the arrows shown in crucible d (in Fig. 4) to the hearths containing the electrodes b and b' .

The use of shunt conductors e^2 , e^3 , e^1 , referred to above, is not absolutely necessary in case the channels uniting the different

hearts are horizontal, because in that case it can be arranged not to withdraw the entire body of fused metal by placing the hole for such withdrawal at a certain elevation 5 above the bottom of the crucible. The invention also applies in the case where the materials contained in the crucible, while being conductors, are not sufficiently fluid to be discharged by pouring. The metal in 10 that case simply serves as a conductor between the different hearts. It will also be understood that the furnace described is also very suitable for the employment of polyphase currents if one hearth is used for 15 each phase, and the connections are suitably arranged.

This furnace which offers great advantages for metallurgical operations can be employed in obtaining metals and their alloys, for reducing as well as refining minerals, for the electrical manufacturing of glass, and in general for many other purposes.

I claim—

- 25 1. An electric furnace comprising a plurality of hearts, a crucible arranged centrally of the hearts, channels connecting the crucible and each of the hearts and so arranged that each hearth is in communication 30 with all of the other hearts, vertical electrodes arranged in each hearth, a source of electric current, a conductor from the positive pole of said source of current and connected to two adjacent electrodes, and a conductor connected to two adjacent electrodes 35 oppositely disposed to said first named adjacent electrodes leading to the negative pole of said source of electric current, substantially as described.
- 40 2. An electric furnace comprising a plurality of hearts, a crucible arranged in

proximity to each of the hearts, channels connecting the crucible and each of the hearts and so arranged that each hearth is in communication with all of the other hearts, vertical electrodes arranged in each hearth, a vertical electrode arranged in the crucible, a source of electric current, a conductor connected to two adjacent electrodes, 45 said conductor being connected with the positive pole of the source of the electric current, a similar conductor connected to two adjacent electrodes oppositely disposed to the first named and connecting with the negative pole of the source of the electric current, and a connection between the source of electric current and electrode arranged in 50 the crucible, substantially as described.

3. An electric furnace comprising a plurality of hearts, a crucible arranged centrally of the hearts, channels connecting the crucible and each of the hearts and so arranged that each hearth is in communication with all of the other hearts, vertical electrodes arranged in each hearth, a source of an 60 electric current, connections between two adjacently disposed electrodes and the positive pole of the source of electric current, conductors between the two adjacent hearts in which said adjacent electrodes are disposed 65 connecting with the two oppositely disposed adjacent hearts, and connections between two electrodes in said oppositely disposed hearts with the negative pole of said source of electric current, substantially as described. 70

In testimony whereof I have signed my name to this specification in the presence of two subscribing witnesses.

CHARLES ALBERT KEIJER.
